UNITED STATES PATENT OFFICE.

RENE E. TATRO, OF KANKAKEE, ILLINOIS.

VENDING-MACHINE.

1,275,325.

Specification of Letters Patent. Patented Aug. 13, 1918.

Application filed October 7, 1915. Serial No. 54,605.

To all whom it may concern:

Be it known that I, RENE E. TATRO, a citizen of the United States, residing at Kankakee, in the county of Kankakee and State 5 of Illinois, have invented certain new and useful Improvements in Vending-Machines, of which the following is a specification.

My invention relates to the class of check controlled apparatus.

10 The primary object of my invention is to provide a device of the class above mentioned consisting of a dispensing container, a check or coin receiver and operating means therefor, the coin serving to actuate the dispensing chamber to release an object upon each operation of the device.

Another object of my invention is to provide a device of the character above-mentioned which is simple in construction, cheap 20 to manufacture, strong and durable and one which is positive in operation.

With the above and other objects in view my invention resides preferably in the construction, combination, and arrangement of 25 parts as hereinafter set forth in the specification and illustrated in the accompanying drawings, in which—

Figure 1 is a vertical sectional view on line 1—1 of Fig. 2 of a vending machine embodying the improvements of my invention.

Fig. 2 is a transverse sectional view of the same taken on the line 2—2 of Fig. 1, looking in the direction of the arrow.

Fig. 3 is a vertical sectional view of my 35 invention taken on the line 3—3 of Fig. 2 in a plane at right angles to that on which Fig. 1 is made.

Fig. 4 is a detail perspective view of an 40 adjusting plate used in the preferred embodiment of my invention.

Fig. 5 is a similar view of a coin receiver.

Similar reference characters indicate similar parts throughout the various views of the drawings.

45 In the drawings, wherein is illustrated the preferred embodiment of my invention, I provide a housing 1 having a vertical partition 2 therein serving to support the horizontal partition 3 having a circular guide 4 thereon, an opening 5 being provided adjacent said guide for a purpose which will hereinafter appear. A plate 6 is carried in the guide 4 and is provided with a radial extension 7 on its periphery. The plate 6 is 50 provided with an inwardly extending V-shaped incision 8 and a portion of the pe-

riphery of said plate is cut away, as indicated at 9 for a purpose which will hereinafter appear. A vertical standard 10 extends upwardly from the plate 6 and is located centrally thereof. The standard 10 serves to support a revoluble container 11 having an outer shell and an inner shell, the inner shell being designated 12 and journaled as at 13 and 15 on said standard 10. 60 The lower peripheral edge of the outer container 11 is provided with a plurality of teeth 16 radially extending from said container for a purpose which will hereinafter appear. The container is divided into a plurality of chambers 17 adapted to be filled 70 with objects to be vended.

A coin slot 18 is provided extending vertically downwardly from the upper end of said housing 1 and having an offset portion 75 19 and a recess 20 therein, said recess 20 having a permanent magnet 21 seated therein. The housing 1 is provided with a top closure 21' to allow of access to the container 11. A closure 22 is hinged at 23 and is actuated 80 by a lug 24 carried by the container 11 so that when the contents have been exhausted, the coin slot will automatically be closed, and remains in closed position until the container is replenished with the proper articles.

The operating mechanism of the invention includes a plunger rod 25 having a handle 26 thereon and slidably mounted in a bracket 27. A suitable coiled spring 28 is disposed 90 about said rod and serves to maintain the same in the position shown in Fig. 3 through contact with a transverse pin 29 carried by said rod 25. The inner extremity of the rod 25 contacts with a hinged coin holder 30, 95 said coin holder comprising a pair of spaced arms 31 and 32 forming the body portion thereof and provided with an opening 33 (see Fig. 5) adjacent their adjoining points to accommodate a bearing pin 34 mounted in 100 suitable brackets 35 carried by one wall of the housing 1.

A suitable coil spring 36 is disposed about said pin 34 and serves to maintain the coin holder in the position shown in Fig. 2, that 105 is, at a point in alinement with the open end of the coin slot 18. The coin holder has an opening 30a which receives the end of a transversely extending arcuate pin 37, which is supported on the casing, said pin 110 being spaced from the periphery of the outer shell of the container 11 such a dis-

2

tance as will accommodate a coin 38 of any predetermined denomination. The coin 38 is held in place by the pin 37 when the coin holder 30 is in the position shown in Fig. 2. 5 As soon as the holder 30 is swung over by the rod 25, the coin 38 will be permitted to gradually slide downwardly by reason of the arcuate movement of the coin holder, and the arcuate shape of the end of the 10 pin 37. The arms 31 and 32 are notched as indicated at 39 so as to allow a portion of the check or coin 38 to engage one of the teeth 16 formed on the container 11. In this manner when a coin is deposited in a slot 15 the same will be caused to drop into the position shown. By delivering an inward movement to the rod 25, the inner extremity thereof will be caused to move the coin holder carrying the coin with the same and 20 causing said coin to engage one of the teeth 16. This will rotate the container 11 through a limited distance allowing the contents of one of the chambers 17 to drop through the opening 8 in the plate 6 and downwardly 25 through a delivering chute 40. The space below the coin holder may serve as a coin receiving chamber and a door 41 may be provided to allow of access to the coin chamber. It will, of course, be understood 30 that as the coin holder moves upon the arc of a circle on its pivot 34, the holder will move arcuately on the pin 37 until the end thereof is reached allowing the coin to drop. Upon releasing the plunger 25, the coin 35 holder will be returned to normal position ready to complete another operation.

It should be understood that the plate 6 may be held against rotary movement, as the container 11 moves thereabove, by the 40 extension 7 engaging the circular guide 4, as illustrated in Fig. 2. Also by having the periphery of the plate cut-away as shown at 9, sufficient space is provided for the swinging of the coin holder.

45 It will be readily understood that for each chamber in the container 11 a corre-

sponding tooth must be provided on the outer periphery thereof so that for each operation of the coin holder, an object will be dispensed from its chamber. It is pointed out that this arrangement may be varied, but the arrangement as shown is preferred. It will also be noted that the magnet will attract magnetic objects deposited and deflect the same in their downward path dropping free of the coin holder. 50 55

While I have shown and described my invention as possessing a peculiar form and construction, it is desired that it be understood that I may make such changes in the 60 details thereof that do not depart from the spirit and scope of the invention as claimed.

Having thus described my invention what I claim and desire to secure by Letters Patent is:

65 In a device of the class described, the combination of a housing, dispensing means carried within said housing, a coin chute carried by said housing, a coin holder positioned below the lower end of said coin chute, said coin holder comprising parallel spaced arms, a vertical opening formed adjacent the inner end of said arms, a pivot pin passing through said opening, thus pivotally supporting said coin holder for permitting the same to be swung in a horizontal plane, means for normally retaining said coin holder below the lower end of said coin chute, means for swinging said coin holder to one side for effecting the operation of the dispensing means by a coin carried by said coin holder, and means associated with said coin holder for temporarily retaining the coin therein until the coin holder has been swung to one side to a predetermined degree. 70 75 80 85

In testimony whereof I affix my signature in presence of two witnesses.

RENE E. TATRO.
